[57] ABSTRACT

An ignition system of capacitor discharge type for internal combustion engines having a DC source, an ignition transformer, a thyristor, a capacitor, a transistor and an oscillator. With all the elements in the system, the capacitor is discharged through the thyristor, transistor and primary winding of transformer when the transistor and thyristor are simultaneously rendered conductive in response to the appearance of a pulse from the oscillator. The capacitor is then charged by a counter electromotive force produced in the primary winding of the transformer in response to subsequent cut-off of the transistor.

FIG. I

FIG.2

IGNITION SYSTEM FOR INTERNAL COMBUSTION ENGINES

This invention relates to ignition systems for internal combustion engines and more particularly to an ignition system of the kind utilizing discharge of a capacitor for the ignition of fuel.

In conventional ignition systems for internal combustion engines employing an ignition coil, a DC source is connected to the primary winding of the ignition coil through an interrupter contact for causing flow of current through the primary winding of the ignition coil while the interrupter contact is in the closed position, and this current flow is interrupted by opening the interrupter contact in synchronism with the ignition timing of the internal combustion engines so that a high voltage induced in the secondary winding of the ignition coil as a result of the opening of the interrupter contact can be utilized for causing spark discharge in an ignition plug connected to the secondary winding of the transformer thereby igniting fuel. However, the conventional ignition system of the type above described has been defective in that the duration of the spark discharge is relatively short and the conditions of ignition tend to be adversely affected by variations of the load on the engine due to the fact that the quantity of energy supplied for the ignition is relatively small. The conventional ignition system has further been defective in that, when the electrode portion of the ignition plug is excessively fouled, a spark is difficult to occur and this results in failure of proper ignition or incomplete combustion of fuel which gives rise to undesirable contamination of atmospheric air.

An ignition system of the type utilizing discharge of a capacitor has been developed recently. This ignition system is advantageous in that the ignition is substantially free from the contamination of the electrode portion of the ignition plug due to the fact that the secondary voltage rises to a predetermined level relatively quickly. However, this ignition system is disadvantageous in that the duration of spark discharge and the energy supplied by the spark discharge have a certain limit. Another disadvantage of this ignition system resides in the fact that complex and expensive means such as an oscillator and a converter are required and the overall size and weight of the ignition system are inevitably increased.

With a view to eliminate such prior art disadvantages, it is an object of the present invention to provide a novel and improved ignition system of the capacitor discharge type for internal combustion engines which can reliably generate sparks without being substantially adversely affected by contamination of the ignition plug or load conditions of the engine.

Another object of the present invention is to provide an ignition system of the type above described in which the spark discharge lasts for an extended period of time and the energy supplied for the ignition can be increased for attaining reliable ignition of fuel.

A further object of the present invention is to provide an ignition system of the type above described which is relatively small in size, light in weight and compact in construction.

Other objects, features and advantage of the present invention will be apparent from the following detailed description of preferred embodiments thereof taken in conjunction with the accompanying drawings, in which:

FIG. 1 is a circuit diagram of an embodiment of the present invention with a part shown by a block; and

FIG. 2 is a circuit diagram of another embodiment of the present invention with parts shown similarly by blocks.

Referring to FIG. 1 showing a preferred embodiment of the present invention, a DC source V_B of, for example, 12 volts is connected to a resistor r_1 through a main switch MS. This resistor r_1 is grounded through an interrupter contact K which is opened and closed in synchronism with the rotation of an internal combustion engine. The main switch MS is connected through a diode D_1 to one end of a primary winding N_1 of an ignition transformer TR and to one end of a secondary winding N_2 of the transformer TR.

The primary and secondary windings N_1 and N_2 of the ignition transformer TR are relatively closely coupled to each other as in, for example, an ignition coil for an automotive vehicle. The other end of the primary winding N_1 is grounded through the collector-emitter path of a transistor Q_1 . The other end of the secondary winding N_2 is grounded through an ignition plug P as is customary in the art. The connection point or node 10 between the resistor r_1 and the interrupter contact K is connected to an input terminal of an oscillator OSC which has two output terminals. The first output terminal of the oscillator OSC is connected to the base of the transistor Q_1 , and the second output terminal of the oscillator OSC is connected through a capacitor C_2 to one end of a resistor r_2 and to one of the electrodes of a diode D_2 . The other end of the resistor r_2 is connected to the main switch MS.

A thyristor Q_2 and a capacitor C_1 are connected in series between ground and the node 12 between the diode D_1 and the ignition transformer TR, and the thyristor Q_2 is disposed in a direction opposite to the forward direction of the diode D_1 . The gate of the thyristor Q_2 is connected to the other electrode of the diode D_2 . Another diode D_3 is connected between the node 14 between the thyristor Q_2 and the capacitor C_1 and the node 16 between the primary winding N_1 of the ignition transformer TR and the collector of the transistor Q_1 . Obviously, the forward directions of these diodes and thyristor should be determined to suit the operation of the system described below. The oscillator OSC may be of any suitable type provided that it can generate a pulse having a predetermined pulse width T_1 every ignition timing, i.e., each time the contact K is urged to the open position.

The ignition system of the present invention having a structure as shown in FIG. 1 operates in a manner as described below. For convenience of description, it is assumed that the main switch MS is turned on when the interrupter contact K is in the closed position. The voltage drop across the contact K is negligible, and therefore, the oscillator OSC is in the deenergized state and the transistor Q_1 remains non-conductive. Current is supplied from the DC source V_B to the capacitor C_1 through the route including the main switch MS, diode D_1 , primary winding N_1 of transformer TR, diode D_3 and capacitor C_1 , with the result that the capacitor C_1 is charged up to substantially the power supply voltage level in the illustrated polarity.

Although the power supply voltage is applied at the same time from the DC source V_B to the gate of the thyristor Q_2 through the resistor r_2 and diode D_2 , this voltage is inactive against the thyristor Q_2 due to the

fact that the potential difference across the thyristor Q_2 is opposite to that in the normal direction. Further, the capacitor C_2 is charged in the illustrated polarity by the current which is supplied from the DC source V_B through the route including the resistor r_2 , capacitor C_2 and oscillator OSC.

The engine starts to rotate in the state in which the capacitors C_1 and C_2 are charged in the manner above described. When the interrupter contact K is urged to the open position in synchronism with the rotation of the engine, a pulse having a predetermined pulse width T_1 as above described appears at the first output terminal of the oscillator OSC and the transistor Q_1 conducts in response to the application of the oscillator output to the base thereof. Thus, current flows from the DC source V_B through the route including the diode D_1 , primary winding N_1 of transformer TR and transistor Q_1 for energizing the transformer TR. The output pulse appearing at the second output terminal of the oscillator OSC is applied at the same time to the capacitor C_2 so that a control signal voltage is applied to the gate of the thyristor Q_2 through the diode D_2 . However, the thyristor Q_2 remains still non-conductive due to the fact that the potential difference there across is opposite to that in the normal direction.

Upon termination of the generation of the first pulse from the oscillator OSC, the transistor Q_1 is rendered non-conductive thereby interrupting the flow of current through the primary winding N_1 of the transformer TR. Thus, a high voltage is induced in the secondary winding N_2 of the transformer TR and spark discharge occurs in the ignition plug P as in the conventional ignition system. At the same time, counter electromotive force is produced in the primary winding N_1 due to a leakage inductance and current flows through the diode D_3 to charge the capacitor C_1 up to a level of, for example, 200 volts, thereby inverting the direction of the potential difference across the thyristor Q_2 . Further, the capacitor C_2 is charged again in the illustrated direction.

Two points should be noted in this connection. In the first place, although a relatively high voltage of, for example, 15 kilovolts is required in order to initiate the spark discharge at the ignition plug P, the voltage required for maintaining the spark discharge after initiation of such discharge may be relatively low or of the order of, for example, 2 kilovolts. Secondly, in the arrangement in which the primary winding N_1 is short-circuited unidirectionally and the DC source V_B is connected there-across, the spark discharge is maintained until the DC source V_B is electrically disconnected from the circuit once the spark discharge takes place. It is considered that the spark discharge can be maintained for the following reasons:

Minute oscillatory variations (of such an extent which will not cause inversion of the polarity) in the magnitude of the spark discharge current or current flowing through the secondary winding N_2 are reflected in the primary current flowing through the primary winding N_1 due to corresponding variations in the magnetic flux in the iron core, and such primary current contacts with the number of magnetic flux lines in the iron core again to induce a secondary voltage against thereby providing the voltage required for maintaining the spark discharge. As a result, the current supplied from the DC source V_B can effectively maintain the spark discharge at the ignition plug P. Further, in such

an arrangement, the input impedance of the transformer TR when locked from the side of the DC source V_B is remarkably reduced upon initiation of the spark discharge at the ignition plug P resulting in an increase in the energy supplied from the DC source V_B through the transformer TR to be released at the ignition plug P. Because of the fact that the discharge route for the capacitor C_1 includes the primary winding N_1 of the transformer TR, these elements constitute an LC oscillation circuit. However, a portion of the oscillatory electromotive force produced in the primary winding N_1 is absorbed by the circuit including the thyristor Q_2 and diode D_3 , and the capacitor C_1 would not be charged in the reverse direction after the discharge of the previously stored charge. Therefore, no natural oscillation is produced by this LC combination.

With the above description in mind, the operation of the system of the present invention at the second ignition timing will now be described. At this second ignition timing, the ignition system behaves in a manner somewhat different from the behavior in the preceding operation.

This is due to the fact that the capacitor C_1 has been charged up to a voltage level considerably higher than the power supply voltage V_B by the charging action carried out in the last stage of the preceding operation. In response to the opening of the interrupter contact K , a second pulse appears from the oscillator OSC, and the transistor Q_1 and thyristor Q_2 are rendered conductive substantially simultaneously in response to the appearance of the pulse from the oscillator OSC.

As a result, the charge stored in the capacitor C_1 is discharged through the primary winding N_1 of the transformer TR. A steeply rising high voltage is thereby applied to the ignition plug P for initiating the spark discharge at the ignition plug P. The current from the DC source V_B is additionally supplied to the ignition plug P in the manner above described so that the spark discharge can be maintained over a period of time corresponding to the duration T_1 of the pulse. Further, a large quantity of energy is supplied for igniting fuel as above described. Upon completion of the discharge of capacitor C_1 , thyristor Q_2 is rendered nonconductive. Therefore, upon disappearance of this pulse, the transistor Q_1 is rendered non-conductive to interrupt the flow of current through the primary winding N_1 of the transformer TR. As a result, a portion of the magnetic energy stored in the iron core of the transformer TR is subsequently released at the ignition plug P as ignition energy to cause spark discharge in a reverse direction for a short period of time. (This corresponds to the spark discharge in the conventional system described in the preface of this specification.). The remaining portion of the magnetic energy produces a counter electromotive force in the primary winding N_1 and this counter electromotive force is supplied to the capacitor C_1 , as described previously, to be held in the capacitor C_1 until the next ignition takes place.

It will be understood from the above description that the present invention provides such an advantage that the ignition can be attained by a large quantity of energy supplied in the form of electrical power from the DC source V_B and maintained over a relatively long period of time corresponding to the pulse width T_1 of the pulse output of the oscillator OSC, in addition to the advantage pertinent to the initiation of spark discharge utilizing the capacitor discharge.

The preferred embodiment of the present invention above described has been so arranged that the oscillator OSC generates a pulse having a pulse width T_1 each time the interrupter contact K is urged to the open position. In a modification of this embodiment, the oscillator OSC may generate two or more pulses T_1 having a short time interval T_2 therebetween.

According to this modification, the transistor Q_1 is turned on and off twice or more every ignition timing and the capacitor C_1 is charged and discharged each time the transistor Q_1 is turned on and off. Further, discharge in one direction due to conduction of the transistor Q_1 and discharge in the opposite direction due to non-conduction of the transistor Q_1 occur repeatedly at the ignition plug P as described previously.

The spark discharge can be substantially continuously carried out when the time interval T_2 between the pulses is relatively short and the next supply of the primary current is started during the period of time in which the spark discharge is sustained by the release of the magnetic energy stored in the iron core after the transistor Q_1 is rendered non-conductive. It is thus not necessarily required to cause discharge of the capacitor C_1 in response to each of these pulses T_1 . In such a case, the thyristor Q_2 is rendered conductive to cause discharge of the capacitor C_1 in response to the first pulse T_1 supplied from the oscillator OSC by suitably selecting the resistance value of the charging resistor r_2 for the capacitor C_2 so that the capacitor C_2 can be insufficiently charged during the period of time T_2 between the pulses. Therefore, the charge in the capacitor C_1 is accumulated each time the primary current is interrupted.

These modifications may be suitably employed depending on the structure of the engine combustion chamber, manner of supplying fuel and other conditions for attaining the desired object.

In FIG. 2 showing another preferred embodiment of the present invention, like reference numerals are used to denote like parts appearing in FIG. 1, and therefore, any detailed description as to such elements is unnecessary. In the following description therefore, those elements which are newly added or replace the corresponding elements in FIG. 1 will be especially described.

Referring to FIG. 2, the node 10 between resistor r_1 and an interrupter contact K is connected to an input terminal of a trigger pulse generator TRIG which has two output terminals. One of the output terminals of the trigger pulse generator TRIG is connected to an input terminal of a first oscillator OSC No. 1, while the other output terminal of the trigger pulse generator TRIG is connected to an input terminal of a second oscillator OSC No. 2. In response to the application of a trigger pulse from the trigger pulse generator TRIG to the first oscillator OSC No. 1, the oscillator OSC No. 1 generates a pulse T_1 having a relatively small pulse width of, for example, 1 ms and this pulse is applied to the base of a transistor Q_1 from the first output terminal of the oscillator OSC No. 1. In response to the application of the trigger pulse from the trigger pulse generator TRIG to the second oscillator OSC No. 2, the oscillator OSC No. 2 generates a pulse T_3 having a relatively large pulse width of, for example, 2 ms. A main switch MS is connected through a diode D_1 to one end of primary and secondary windings N_1 and N_2 of an ignition coil IGC and to the cathode of a thyristor Q_2 . Further,

the main switch MS is grounded through a primary winding N_1' of a transformer TR' and a transistor Q_3 which are connected in series.

The base of this transistor Q_3 is connected to an output terminal of the second oscillator OSC No. 2. A secondary winding N_2' of the transformer TR' is grounded directly at one end thereof and is connected at the other end thereof to the node 14 between the thyristor Q_2 and a capacitor C_1 through a diode D_4 . A capacitor C_2 is connected at one of the electrodes thereof the gate of the thyristor Q_2 through a diode D_2 and at the other electrode thereof to the second output terminal of the first oscillator OSC No. 1 to receive the pulse T_1 therefrom. A protective resistor r_3 may be disposed in parallel with the transistor Q_1 .

In the operation of the second embodiment of the present invention shown in FIG. 2 which will be now described, it is needless to waste words for the operation of those parts which have been described already with reference to FIG. 1. In response to the turn-on of the main switch MS, the capacitor C_2 is charged in the illustrated polarity through the charging resistor r_2 . At the same time, the capacitor C_1 is charged up to substantially the power supply voltage V_B through the diode D_1 , primary winding N_1 of ignition coil IGC and diode D_3 . The remaining parts of the circuit are still not in operation.

When the interrupter contact K is urged to the open position in such a situation in synchronism with the rotation of the engine, the trigger signal is applied from the trigger pulse generator TRIG to the first and second oscillators OSC No. 1 and OSC No. 2. In response to the application of the trigger pulse, the pulses of predetermined duration, that is, the pulse T_2 having a relatively small pulse width and the pulse T_3 having a relatively large pulse width appear at the output terminals of the first and second oscillators OSC No. 1 and OSC No. 2 respectively so that the transistor Q_1 , thyristor Q_2 and transistor Q_3 are rendered conductive almost simultaneously. As a result, energizing current flows through the primary winding N_1 of the ignition coil IGC and through the primary winding N_1' of the transformer TR' and magnetic energy is accumulated in the iron core of the ignition coil IGC and transformer TR'. However, no current flows through the thyristor Q_2 .

The transistor Q_1 is cut off before the transistor Q_3 is cut off due to the fact that the pulse width of the pulse T_1 is smaller than that of the pulse T_3 . The cut off of the transistor Q_1 results in interruption of the flow of the primary current in the ignition coil IGC and a portion of the magnetic energy accumulated in the iron core of the ignition coil IGC is released at an ignition plug P as spark producing energy. The remaining portion of the magnetic energy provides a counter electromotive force in the primary winding N_1 of the ignition coil IGC and the capacitor C_1 is charged thereby through the diode D_3 . Then, when the transistor Q_3 is rendered non-conductive, the magnetic energy accumulated in the iron core of the transformer TR' connected thereto induces a voltage in the secondary winding N_2' of the transformer TR' and this voltage is applied from the secondary winding N_2' to the capacitor C_1 through the diode D_4 for charging the capacitor C_1 . The charge supplied to the capacitor C_1 from the primary winding N_1 of the ignition coil IGC is subject to slight variations depending on the condition of release of the energy at the ignition plug P. However, the charge supplied from the

secondary winding N_2' of the transformer TR' compensates for such variations so that a voltage sufficient for initiating spark discharge at the ignition plug P in the next ignition timing is built up in the capacitor C_1 .

When the interrupter contact K is opened at the next ignition timing and the trigger signal is applied to the first and second oscillators OSC No. 1 and OSC No. 2, the pulses T_1 and T_3 are applied to the respective transistors Q_1 and Q_3 to render these transistors conductive.

The gate control signal is applied to the gate of the thyristor Q_2 almost simultaneously with the result that the charge stored in the capacitor C_1 is discharged by way of the discharge route including the thyristor Q_2 , primary winding N_1 of ignition coil IGC and transistor Q_1 . An abruptly rising high voltage is thereby induced in the secondary winding N_2 of the ignition coil IGC to initiate spark discharge at the ignition plug P. In this case, the natural oscillation that may occur in the LC discharge route is absorbed by the circuit including the diode D_3 and thyristor Q_2 . Thus, spark discharge with large energy is continued at the ignition plug P by the electrical power supplied from the DC source V_B during the period of time in which the transistor Q_1 remains conductive. Upon completion of the discharge of the capacitor C_1 , the thyristor Q_2 is rendered nonconductive. Thereafter, the capacitor C_1 is re-charged upon disappearance of the pulses T_1 and T_3 to prepare for the next ignition.

The second embodiment of the present invention has been described with reference to the arrangement in which one pulse T_1 of predetermined duration and one pulse T_3 of predetermined duration appear from the first and second oscillators OSC No. 1 and OSC No. 2 respectively every ignition timing. In a modification of such embodiment, the first oscillator OSC No. 1 may generate two or more pulses T_1 having a time interval T_2 therebetween in response to the application of one trigger pulse input from the trigger pulse generator TRIG, and the second oscillator OSC No. 2 may generate a pulse T_3 whose duration is larger than the total sum of these pulses T_1 and time intervals T_2 .

Further, the relation between the time interval T_2 and the pulse width of the pulse T_1 in such a case may be such as is considered in the modifications of the first embodiment. Further, although the transformer TR' in FIG. 2 is shown having a secondary winding, it may have merely a primary winding wound around an iron core so that a counter electromotive force produced in the primary winding may be derived as magnetic energy for charging the capacitor C_1 as shown in FIG. 1.

The embodiments of the present invention above described have been illustrated as the type provided with an interrupter contact K which is mechanically opened and closed in synchronism with the rotation of the engine. However, the system having such mechanical on-off means is merely illustrative of one form of the present invention and those skilled in the art can easily make modifications in which electromagnetic, optical or any other suitable means are employed in lieu of such mechanical on-off means for controlling the oscillators or trigger signal generator. It should be understood therefore that such modifications are also included in the scope of the present invention in addition to the preferred embodiments above described.

What is claimed is:

1. An ignition system for internal combustion engines comprising an ignition transformer means having a pri-

mary and a secondary winding, and said primary winding being grounded at one end thereof through a transistor and connected at the other end thereof to a DC source through a diode, said the other end of said primary winding being further grounded through a thyristor and a capacitor connected in series, and said secondary winding being connected at one end thereof to an ignition plug, an oscillator means for generating at least one pulse having a predetermined pulse width every predetermined ignition timing of the engine in synchronism with the rotation of the engine, means for coupling the output pulse of said oscillator means to the base of said transistor, means for coupling the output pulse of said oscillator means to the gate of said thyristor, said thyristor, said transistor and said primary winding of said transformer means providing a discharge circuit for said capacitor when both said transistor and said thyristor are rendered conductive substantially simultaneously in response to the application of the output pulse from said oscillator means, and means for charging said capacitor by a counter electromotive force produced in said primary winding of said transformer means when said transistor in the conducting state is rendered non-conductive.

2. An ignition system for internal combustion engines as claimed in claim 1, wherein said oscillator means generates at said predetermined ignition timing at least two pulses having a predetermined pulse width with a relatively short time interval therebetween.

3. An ignition system for internal combustion engines as claimed in claim 2, wherein only one of the output pulses of said oscillator means is coupled to the gate of said thyristor at said predetermined ignition timing.

4. An ignition system for internal combustion engines as claimed in claim 1, further comprising a second oscillator means and a second transformer means having a primary and a secondary winding, said primary winding of said second transformer means being grounded at one end thereof through a second transistor and connected at the other end thereof to said DC source, while said secondary winding of said second transformer means being connected at one end thereof to said capacitor through another diode and grounded directly at the other end thereof, and said second oscillator means being operative in such a manner that an output pulse, which appears substantially simultaneously with the appearance of the output pulse from said first oscillator means and disappears after the disappearance of the output pulse from said first oscillator means, is generated from said second oscillator means to be applied to said second transistor for maintaining said second transistor conductive during such period of time.

5. An ignition system for internal combustion engines as claimed in claim 2, further comprising a second oscillator means and a second transformer means having a primary and a secondary winding, said primary winding of said second transformer means being grounded at one end thereof through a second transistor and connected at the other end thereof to said DC source, while said secondary winding of said second transformer means being connected at one end thereof to said capacitor through another diode and grounded directly at the other end thereof, and said second oscillator means being operative in such a manner that an output pulse, which appears substantially simultaneously with the appearance of the first output pulse from said first oscillator means and disappears after the disappearance of the second output pulse from said first oscillator means, is generated from said second oscillator means to be applied to said second transistor for maintaining said second transistor conductive during such period of time.
